(21) Appl. No.: **29/125,475**

(57) **CLAIM**

(22) Filed: **Jun. 24, 2000**

The ornamental design for a shower mounted douche apparatus, as shown and described.

(51) LOC (7) Cl. **24-01**

DESCRIPTION

(52) U.S. Cl. **D24/108; D24/111**

FIG. 1 is a perspective view of a shower mounted douche apparatus showing my new design, with the tube shown broken for ease of illustration. The broken line showing is for illustrative purposes only and forms no part of the claimed design.
